GRID STRUCTURE FOR ELECTRON DISCHARGE DEVICES

Simeon Weston, New York, N. Y., assignor to Federal Telephone and Radio Corporation, New York, N. Y., a corporation of Delaware

Application March 23, 1945, Serial No. 584,422

10 Claims. (Cl. 250—27.5)

1

The present invention relates to electron discharge devices.

An object of the present invention is the provision of an improved electron discharge device.

Another object of the present invention is the provision of an improved electrode assembly for electron discharge devices and particularly one adapted to be mounted on a disc extending outwardly through the envelope of the device and serving as an external grid terminal.

Another object of the present invention is the provision of an improved grid assembly and mounting therefor which provide good heat dissipation, and thereby maintain the grid at a relatively low temperature, thus minimizing grid emission.

Another object of the present invention is the provision of an improved grid assembly wherein the grid wires are kept taut under tension so as to maintain exact spacing between the grid wires themselves as well as between the grid wires and other electrodes.

Still another object of the present invention is the provision of an improved electrode assembly and mounting whereby the electrode may be readily and accurately mounted within an electron discharge device.

Other and further objects of the present invention will become apparent and the invention will be best understood from the following description of an embodiment thereof, reference being had to the drawing, in which:

Fig. 1 is an enlarged sectional view of an electron discharge device embodying my invention;

Figs. 2 and 3 are sections taken substantially along the lines 2—2 and 3—3 respectively of Fig. 1;

Fig. 4 is a detailed view of the grid assembly;

Figs. 5 and 6 are similar detailed views of the grid assembly as it is being mounted on the grid disc.

Referring now to the drawings, the electron discharge device or tube illustrated is similar in many details to the tube described and claimed in the copending application of J. Glauber-1, for "Assembly for electron discharge device," Serial No. 542,089, filed June 26, 1944, and the present invention may be considered in one aspect as being an improvement thereon.

2

Referring now particularly to Fig. 1 of the drawings, the electron discharge device has an envelope generally designated by the numeral 1 including insulating portions 2, 3 and 4, to which are sealed conductive discs 5, 6, and 7, with a skirt 8 depending from and integral with disc 7, and a reentrant metallic closure member 9.

Disc 5 serves as the upper closure member of the tube and is sealed to one end of insulating portion 2. Disc 5 also serves as the anode terminal and support, and is provided with a depressed or dished portion 10 at the center thereof to the bottom of which is welded the anode 11. Disc 6 is sealed between insulating portions

15 2 and 3 and serves as the external grid terminal and grid assembly mount. A rectangular opening 12 is formed within disc 6, and adjacent said opening the disc 6 is provided with a thinned portion 13 having a plurality of internally threaded holes 14 therein. The grid assembly 15 (see Figs. 4 through 6), which is mounted on disc 6, consists of a relatively thick conductive plate 16 of good conductive material, and preferably somewhat resilient, on which the grid 17, consisting of a plurality of relatively thin wires 18, is mounted and supported, said grid wires being of conductive material, preferably nickel or molybdenum.

The grid assembly 15 is preferably made in the following way:

A rectangular opening 19 is formed in the middle of the plate and flanges 20 are bent upward from said plate substantially normal thereto and at opposite ends of said opening. The height of said flanges determines the positioning of the grid, as will be apparent from the subsequent description, and it may be necessary to machine the tops 21 of said flanges to obtain the precise height required. The plate is then curved or bent as illustrated in Fig. 4. The grid 17, consisting of its plurality of grid wires 18, is then welded or brazed to the tops 21 of said flanges. Any suitable brazing material may be employed for brazing the grid to the tops 21. A gold copper alloy has been found satisfactory for this purpose.

The grid wires 18 are not pulled taut when they are brazed to the tops 21 but are relatively loose or somewhat slack and not under tension. To pull said grid wires taut and bring them under tension, the plate 16 which is curved at this

stage, is placed under pressure and bent into a substantially flattened configuration.

Plate 16 may be flattened and mounted in one operation by inserting said plate inside the envelope 1 of the tube so that the plate 16 touches the thin portion 13 of disc 6 (see Figs. 1 and 5), inserting screws 22 through suitable holes 23 in plate 16 and threading said screws into the internally threaded openings 14 of the thin portion 13. As will be clear from Fig. 5, as the screws 22 are tightened, the plate 16 is flattened, thus bringing the grid wires 18 under tension and at the same time mounting the grid assembly and accurately positioning the grid within the tube.

If desired, as for example to avoid too much strain on the threads of screws 22 and opening 14, plate 16 may be partially straightened out prior to insertion in the envelope. This may be done in a vise or in any other suitable fashion. The final straightening may then be accomplished by screws 22.

Because of the flattening of member 16, the grid wires will be maintained under tension and will not sag. Furthermore, it will be seen that because of the relative thickness of plate 16, said plate will quickly conduct heat from the grid to disc 6 which will, in turn, dissipate said heat outside the tube envelope.

Disc 7 may be used as the cathode terminal and, together with its skirt 8, serves to support a cathode mount 24 of the type described in the aforesaid J. Glauber-1 application. The cathode mount 24 consists of a conductive frame 25 having insulating spacers 26 mounted at opposite ends thereof and secured by eyelets 27. The spacers 26 are provided with openings 28 therein in which is inserted a cathode sleeve 29 having a heater 30 therein. The heater 30 is connected by flexible leads 31 to lead wires 32 extending through and sealed in the insulating portion 4 at the bottom of the tube. The cathode sleeve 29 has a small tab 33 struck therefrom and bent adjacent to and welded or brazed to a similar tab 34 from the conductive frame 25. This forms a direct current connection between the cathode sleeve and the frame 25 which has low thermal conductivity. A low impedance high frequency connection between said sleeve and said frame is produced by the inherent capacity therebetween.

Frame 25 of mount 24 is fastened at its lower end, as by welding, to a relatively stiff metallic member 35 which is in turn fastened to the skirt 8. The mount 24 is further maintained in position by shoulders 36 formed in the upper corners of the spacers 26 which shoulders bear against the bottom and sides of the portions of disc 6 adjacent opening 12.

The tube is preferably assembled in the following order:

After discs 5, 6, and 7 with its skirt 8, have been sealed to insulating portions 2 and 3 and the anode 11 mounted on disc 5, the grid assembly is then put in place as hereinbefore described. Next the mount 24 carrying the cathode sleeve 29 and heater 30 is inserted and secured in place by means of member 35. The leads 31 from the heater are fastened to lead wires 32. Then the assembly consisting of insulating portion 4 and reentrant closure member 9 is inserted and secured in place as by means of brazing at the point indicated by numeral 37. The tube is then evacuated through stem 38 and otherwise treated in the manner well-known in the art.

While I have described details of a grid assembly and mounting and a process therefor,

it will be seen that much of this may be employed for other electrodes. Accordingly while I have described above one structure and the specific details of a process embodying my invention, it is to be clearly understood that this description is made only by way of example and not as a limitation on the scope of my invention as defined in the accompanying claims.

I claim:

1. An electrode structure for an electron discharge device comprising a bent plate, a multi-strand electrode mounted on said plate, a mount for said plate and said electrode and means holding said plate in an altered shape against said mount for bringing said electrode under tension.

2. An electrode structure for an electron discharge device comprising a curved conductive plate provided with an aperture, flanges extending from said plate, an electrode extending across said opening on the concave side of said plate and secured to said flanges, and means holding said plate in a straightened shape to bring said electrode under tension.

3. An electron discharge device having an envelope and a conductive disc extending outwardly through the envelope and forming an external terminal, said disc having an opening therein within the envelope, a curved conductive plate within the envelope having an opening therein, a pair of flanges extending from said plate adjacent its opening, a planar grid extending across the plate opening on the concave side of said plate and secured to said flanges, and screw means fastening said plate to said disc in a flattened shape for bringing said electrode under tension.

4. An electron discharge device having an envelope, and a metallic disc partially within the envelope and extending through and sealed in said envelope and forming an external connector, said disc having an opening therein within the envelope, a conductive plate within the envelope having an opening therein, a pair of flanges extending from said plate, said plate being normally curved with said flanges on the concave side, a planar grid extending across the opening of said plate on the concave side thereof and secured to said flanges, and means fastening said plate in straightened position to said disc with the opening of said plate within the opening of said disc.

5. A grid structure for an electron discharge device comprising a bent conductive plate having an opening therein and a concave side, a grid extending across said opening and secured to said plate on said concave side, a mount for said grid and plate, and means securing said plate to said mount, said plate being straightened against said mount for bringing said grid under tension.

6. The method of making an electrode assembly comprising mounting the electrode on the concave side of a curved support and straightening said support to bring said electrode under tension.

7. The method of making a grid assembly comprising forming an opening in a conductive member, bending said member, mounting an electrode on the concave side of said member extending across said opening, and straightening said member to tauten said electrode.

8. The method of making an electrode assembly comprising forming an opening in a flat conductive plate, forming flanges extending angularly to the plane of said plate, bending the plate so that the surface from which the flanges project is substantially concave, mounting the elec-

trode on said flanges and straightening the plate to bring the electrode under tension.

9. A method of mounting an electrode in an electron discharge device envelope having a mounting member therein comprising mounting said electrode on the concave side of a support having a given configuration, and inserting said support inside the envelope adjacent said mounting member and forcing said support against said mounting member to flatten said support and bring said electrode under tension.

10. A method of mounting a grid in an electron discharge device envelope having a disc sealed to the envelope, said disc having an opening therein within the envelope, comprising mounting the grid on the concave side of a curved metallic plate, inserting the plate inside the envelope adjacent said disc with the grid aligned with the opening of said disc and forcing the plate under tension against the disc.
